UNITED STATES PATENT OFFICE.

JOHN H. ELWARD, OF POLO, ILLINOIS.

ENGINE-FURNACE.

SPECIFICATION forming part of Letters Patent No. 276,372, dated April 24, 1883.

Application filed October 20, 1882. (No model.)

To all whom it may concern:

Be it known that I, JOHN H. ELWARD, a citizen of the United States, residing at Polo, in the county of Ogle and State of Illinois, 5 have invented certain new and useful Improvements in Boiler Attachments for Steam-Engines, of which the following is a specification, reference being had therein to the accompanying drawings.

Figure 1 is a longitudinal section of a boiler-furnace embodying my improvements, said figure showing also a sufficient portion of the boiler and the transporting devices to clearly illustrate the method of applying the features 15 of my invention. Fig. 2 is an end view without the supporting mechanism. Fig. 3 is an end view, showing a hopper for feeding chaff or other light material. Fig. 4 is a side elevation of that shown in Fig. 3. Fig. 5 shows 20 the said hopper in another position. Fig. 6 is a perspective of a part of the door. Fig. 7 is a sectional view of the steam-exhaust pipe and nozzle. Fig. 8 shows the door on the inside of the furnace detached and the rod by which 25 it is actuated.

The features of my invention are especially applicable to the traction or portable engines which are transported from one place to another and are employed for thrashing and other 30 farming purposes. The ground-wheels of the boiler proper, the engine, and the driving mechanism may be of any desired construction, though I prefer to employ those shown in the patents heretofore granted to me.

In the drawings, A² represents the outer shell of the boiler. This shell extends from the rear end plate, a, to the plates B B'. Within the boiler is situated the large fire-flue C', extending from the rear plate a to the front 40 plate c', passing through plate c. Between the rear plates, a and c, is the rear chamber, C, and between the front plates, c' and B B', is the front chamber, C². The fire-flue C' extends from the outer rear wall, a, to the inner front wall, c'. The return-flues are represented by D, and communicate at the ends with the chambers C and C². The fire-flue C' is situated eccentrically relatively to the outer shell of the boiler. The rear end of the fire-flue is 45 utilized as a furnace-chamber, this chamber being represented by D'.

D² is the hearth-plate, situated across the

furnace, at the rear end, at a suitable distance from the bottom of the main flue.

B³ is the bridge-wall, situated at a proper point within the flue, this wall and the plate D² being adapted, as shown, to sustain the grate-bars d. The bridge-wall D³, unlike the bridge-walls heretofore used, is not attached in any way to the fire-flue, but is situated loosely 55 therein, and can be removed at any time. It is constructed to have the wall D³, one or more webs, D⁴, and two or more hooks or seats at d². The web or webs D⁴ support the wall vertically, and the grate-bars d, seated in the hooks 60 or seats d², prevent the wall from moving horizontally. The hearth-plate D² is provided with hooks or seats d³, similar to those at d².

Beneath the rear end of the boiler and furnace is situated the ash-box or pan E. It is 70 elongated, and communicates with the interior of the main flue by a passage at E' running upward beneath the plate D². Through this passage E' the ashes which drop from the grate may escape into the pan after being 75 drawn outward by the operator. This passage E' is situated behind the water-space of the boiler. Forward of the rear end of the plate c—that is to say, forward of the rear end of the water-space—there is formed an air-opening, E². This is situated directly beneath the grate, and is for the purpose of insuring a much greater draft than can be obtained by the ordinary draft-openings, such increase of draft being necessary when burning the light 80 materials, to be hereinafter described. This air-opening can, when desired, be closed by a sliding door, e, carried by a rod, e', Fig. 8, running to the rear end of the furnace. This aperture is formed by means of separate pieces of boiler-iron, arranged as shown, and joined to the shell 85 of the boiler and to the shell of the fire-flue. A water-space of about three inches is left at a² between the apertures E² and the rear inner wall, c. When required, this aperture E² may 90 be also used for removing ashes or other material from the furnace-chamber. The ash-pan E is provided at the ends with swinging doors e², and by opening these any desired amount of air may be allowed to pass upward into the 95 furnace. I prefer, however, to admit air to the ash-pan by means of doorways in the side of the pan, provided with doors, as shown at E⁴. The doorway to the furnace is closed by 100

a door formed of the parts F F' F². The outer part, F², is of substantially the same dimensions as the doorway, and is hinged on a vertical line, as shown at f. The part F' forms a draft-door, whereby air can be admitted below the hearth-plate and the grate. The central part, F, of the door is hinged at its lower edge to the part F² on a horizontal line, as at f', so that it can swing vertically into and out from the furnace, as shown in dotted lines in Fig. 1. Its dimensions are somewhat greater than those of the opening in the part F², so that when it (said part F) is in a vertical position it fits tightly against the inside of part F². X is a weight attached to the vertically swinging door by means of a rod, X', which passes through the weight, and to which the weight is secured adjustably by a set-screw.

In Fig. 6, I have shown a very simple but advantageous device for holding open the part F', and also for locking it when closed. It consists of a wedge-shaped piece, F⁵, of metal, pivoted near its thicker end at f³. If the door be partially opened and the thinner edge of the wedge be dropped behind the door, it will be held outward, and it can even be supported in a position substantially horizontal. On the other hand, if the wedge be raised and the door closed and the wedge then be dropped again into the position shown in Figs. 2 and 3, it will securely hold it shut.

F⁶ F⁷ are elongated curved doors above and around the upper portion of the fire-flue door. They are hinged on substantially the central line of the boiler, and are fastened by means of catches at F⁷. These doors and the apertures which they close render it very easy to clean the returning-flues and the rear smoke-chamber around the fire-flue. When coal or wood is to be used as fuel the whole door is opened on the hinge at f, that the fuel may be introduced. When straw or other similar light material is to be used as fuel it is to be pressed against the door F, which will yield and swing downward to the hearth-plate to permit the introduction of the fuel. After the fuel has passed the door and the fork or other implement has been withdrawn the door is again raised to the vertical position by the weight X. The vertically swinging door is provided with numerous perforations, f², or with registers, or with large apertures, as shown at V, Fig. 3.

Heretofore it has been customary when burning straw to attach to the front of the boiler or furnace a tube or trough, this tube or trough connecting with or forming a part of the fire-door or furnace-door itself. I however dispense entirely with such tubes, as there are incident to them many disadvantages which I obviate. It will be seen that I employ a door situated substantially as is situated the ordinary furnace-door. The center of this horizontally swinging door is provided with a vertically swinging part, as described. This arrangement enables me to readily feed fuel of either class—that is to say, either hard fuel, such as wood or coal, on the

one hand, or light fuel, such as straw, on the other—without necessitating that any part should be removed or changed. Moreover, in using these constructions having the aforesaid feeding-tubes, the object has been to prevent as much as possible the entrance of air to the furnace where the straw was being consumed; but in my present construction my object is exactly the opposite of this—that is to say, in burning the straw and other similar material I introduce a great amount of air to secure perfect combustion, and for this purpose I provide three entrances at the end, as shown at f² and V, and with these combine the bottom aperture, E², below the grate. The air-entrances thus arranged prevent any clogging by unburned masses of straw and insure the complete combustion of all the fuel.

Another object of my invention is to utilize the chaff or dust which is obtained by thrashing the heads of the wheat or other grain when such grain is harvested without cutting the straw by the operation ordinarily called "heading," for, as will be readily understood, there is but little straw passes through the thrashing-machine that can be utilized as fuel. This chaff cannot be fed through an ordinary furnace-door, nor through the tubes hereinbefore alluded to; but I have, after considerable experimenting, found that it can be utilized for fuel if it be fed to the furnace through a narrow throat to which there is access independently of the ordinary furnace-door, such throat causing it to enter in a sheet or spray, which permits combustion to great advantage. In the drawings I have shown a method of introducing chaff in such manner that it can be made available to produce great heat.

T represents a hopper inserted into the rear end of the furnace. It is as wide as practicable in the direction across the furnace, but is made to contract in the longitudinal direction of the furnace until it forms a narrow throat or passage, t.

I prefer the construction of hopper and feeder shown in Figs. 3 and 4; but, if desired, it may be situated at the side of the door F F' F², as shown at T', or it may be inserted through the side of the shell and the side of the fire-flue. In either case it is provided with an outwardly swinging door, T². It is not inserted in nor has it any connection whatever with the ordinary door itself of the furnace. The chaff or dust is sifted, as it were, down into the furnace through the long, narrow throat, and by opening the register V or by means of the openings f², and by "nozzling down" the exhaust-pipe in the smoke-stack—that is, reducing the escape-orifice of the exhaust-pipe in the manner to be hereinafter described—a strong draft is caused, and the stream of dust and chaff becomes instantly dry and ignited, and the flame which results is carried through the fire-flue and the return-flues, causing great heat.

The devices for narrowing the nozzle of the exhaust-pipe have an intimate relation with

the devices above described used in burning light material.

N², Fig. 2, is the exhaust-pipe, running in the usual manner into the smoke-stack. I attach to the end in the stack an elbow, N, Fig. 7, having a flat flange, n. On this flange fits and slides a cut-off plate, S, attached to a cogged arm, H³, projecting outwardly through the smoke-stack. With this cogged arm engages a small pinion, N⁴, mounted on a shaft, N³, which can be rotated from either end of the engine by means of hand-wheels, as shown at H⁶. Instead of these devices, the arm H³ may have a handle for operating it directly. By these devices I can easily cause the draft to be greatly increased, so as to insure the perfect combustion of straw or chaff or other light material when used as fuel.

By having air-apertures in the front end of the furnace, as I have shown in the door above the grate, I can by increasing the draft assist in spreading the chaff over the fire-bed and preventing its accumulating in any one place, and by means of the devices below the furnace I can supply a strong, copious, independent current of air to effect a perfect and rapid combustion of the chaff. However, I do not wish to be limited under all circumstances to the combination of the two sets of devices for the admission of air—one above the grate and the other below—for many of the advantages which I attain can be secured if the front end of the furnace is closed when the draft is strong enough to draw chaff away from the narrow throat and properly spread it.

While going uphill much trouble is generally experienced from the falling of cinders, ashes, &c., through the rear door. Upon the rear platform I place a receptacle adapted to catch and retain any materials that may drop from the furnace. It is represented at E⁷. It is constructed of sheet metal, and is formed to have a curved and sloping mouth at c', which permits it to be fitted tightly against the end of the furnace, and at the same time prevents interference with any of the other parts. It may be secured upon the platform by any preferred means.

O' is a large door in the front end, adapted to permit free access to the front part of the main fire-flue. This door has an aperture covered by a small supplemental door, O². It is sometimes necessary to have access to the front smoke-chamber or the fire-flue when it is not desirable to make an opening as large as would be made by opening the door O'. Such limited access is provided by the door O².

Beneath the front end of the boiler there is a receptacle, P, into which fall cinders and ashes that are carried to the front smoke-chamber, O².

I do not herein claim any of the features direct-

ly combined with the steam-dome for conducting dry steam therefrom, as I have made this the subject-matter of another application which I have filed. Nor do I claim herein any of the features pertaining to the device for heating feed-water, preferring to claim all such patentable matters in the other applications, which, together with this case, are divisions of the application filed December 29, 1881.

What I do claim is—

1. In a portable engine, the combination, with the furnace, of a door constructed of an outer horizontally-swinging portion pivoted at its edge, whereby the whole doorway can be opened, and an inner part pivoted on a horizontal line along its edge and arranged to swing inward toward the furnace and outward therefrom, substantially as and for the purposes set forth.

2. In a portable engine, the combination, with the furnace D' and the hearth-plate D², of the door having the outer horizontally-swinging portion, F², the part F, pivoted to said part F² and adapted to swing into and out from the furnace, and the part F', for closing the ash-pit below the hearth-plate, substantially as set forth.

3. In a portable chaff-burning engine-furnace, the combination of a door for the admission of coal, provided with apertures for the admission of air above the grate, the hopper T, having a narrow throat for the admission of chaff independently of said door, means in the smoke-stack for increasing the strength of the draft through the furnace, and means for admitting air freely into the furnace independently of the door by which coal is introduced, substantially as set forth.

4. In a portable chaff-burning engine-furnace, the combination of a horizontal grate, a door for supplying coal, a contracted passage-way independently of said door for supplying chaff, means in the smoke-stack for producing a strong draft through the furnace, and an air passage-way below the furnace, with an air-entrance directly below the grate for admitting air to the fire-bed independently of the doors at the end of the furnace, substantially as set forth.

5. The combination, with the furnace D', of the upper rear door, F², the lower door, F', hinged to said upper part, F², and the locking-wedge F⁶, arranged and operated substantially as set forth.

In testimony whereof I affix my signature in presence of two witnesses.

JOHN H. ELWARD.
